J. Waldie.

Straight Knitting Mach.

N° 80,887.

Patented Aug. 11, 1868.

United States Patent Office.

JAMES WALDIE, OF IPSWICH, MASSACHUSETTS, ASSIGNOR TO HIMSELF AND
GEORGE KENNEDY, OF SAME PLACE.

Letters Patent No. 80,887, dated August 11, 1868.

IMPROVEMENT IN KNITTING-MACHINES.

The Schedule referred to in these Letters Patent and making part of the same.

TO ALL WHOM IT MAY CONCERN:

Be it known that I, JAMES WALDIE, of Ipswich, in the county of Essex, and State of Massachusetts, have invented certain Improvements in Machinery for Weaving Striped Hose, &c., of which the following is a full, clear, and exact description, reference being had to the accompanying drawings, making part of this specification, in which—

Figure 1 is a perspective view of my improvements applied to a machine for weaving striped hose.

Figure 2 is a transverse vertical section through the centre of the same.

Figure 3 is a perspective view of the notched flange-wheel, with its weighted arms or levers, the wheel being revolved by the drivers, so as to cause the arms or levers to engage at the required times with the several thread-carrying guide-bars.

To enable others skilled in the art to understand and use my invention, I will proceed to describe the manner in which I have carried it out.

In the said drawings, A is the framework, in the top of which is formed a grooved way, a, for the table B to slide therein. Rising from each end of this table is a standard, b, to which is secured the cord, which passes over guide-pulleys, and around the "slur-wheel," which is operated by a treadle under the machine, for producing the alternate forward and back motion required. The above-mentioned cord, guide-pulleys, "slur-wheel," and treadle, forming no part of my invention, and being of common construction, are not represented in the drawings.

The tops of these standards b are provided with open slots, in which rests a bar, C, the ends of which are rounded or bevelled off, as shown at 5, fig. 1, in order that they may ride up over the rounded surface, 6, of stops D, placed, one at each end of the top of the framework. To opposite sides of the sliding bar C, at 7, are secured the bent arms E, to the lower portions, e, of each of which is pivoted, at 8, the lever or driver F, which is pushed forward by the sliding bar C, so as to engage with the teeth or notches d formed in the periphery of a wheel, G, which serves as a ratchet, and is placed underneath or forms the under side of a cam-wheel, H, which fits loosely upon a short stationary shaft or stud, I, proceeding up from the table B.

The sliding bar C is provided with two pins, e, which regulate the throw of the sliding bar C, and serve as stops for preventing the lever or driver from turning the ratchet-wheel G more than the distance between two teeth, d. Each driver, F, is provided with a spring at its back, to insure its engaging with the ratchet.

The top of the short stud I is cut away for the reception of a slotted bar, K, which rests upon the cam-wheel H, in a direction transversely with the machine, a pin, f, passing through the stud and slot g, to allow it to be slid back and forth, in a manner and for a purpose now to be explained.

On suitable ways, L, M, and N, in front, and that, O, at the back of the machine, rest the several bars, L' M' N' O', to which the thread-guides h i j k, carrying the different-colored yarns, are attached, all of the thread-guides on the same bar carrying the same colored yarn, different from that carried by the guides on each of the other respective bars. l m n are forked pieces, secured to and projecting vertically up from the several bars L' M' N' O'.

One end of the slotted bar K is provided with a projection, p, which is made to engage with the forked pieces l m n, and thus cause the several bars L' M' N' O' to move back and forth on their ways, L M N O, and carry the guides h i j k, only one bar, L' M' N' O', and its series of guides, (carrying the desired color to be woven,) being operated at a time. The manner in which the slotted bar K is thrown into connection with either of the forked pieces h i j k, to move the bar and guides carrying the color required, will now be described.

To the end of the slotted bar K (opposite that bearing the projection p) is secured one end of a spring, r, the other end of which is fastened to the pin f, passing through the slot g. From the under side of the slotted bar K projects a pin, s, which bears against the periphery or exterior edge of the cam or eccentric, H.

As the driver or drivers engage with and turn the ratchet G, the cam-wheel is simultaneously revolved.

thereby, and the slotted bar K, through the connections above described, is made to move in the direction of the arrow 5 by the recoil of the spring r, so as to engage with either of the forked pieces l m n, on the guide-bars L' M' N', (at the front of the machine,) sufficiently long to weave the desired number of courses, of the color required, while the bar K is pressed forward in the direction of the arrow 6, so as to engage with the forked pieces, (not shown in the drawings,) but attached to the bar O, sliding it, and carrying therewith the thread-guides k, by the periphery of the cam H, pressing the pins in this direction against the resistance of the spring r.

The periphery of the cam is provided with notches z, the distance between which is such, that, as the cam revolves, the sliding bar will continue its connection with any particular guide-bar sufficiently long to allow of its being slid back and forth to weave the desired number of courses of that color of yarn.

By the above-described construction, I am enabled, by the employment of one driver, to weave any number of even courses of three or four colors. The cam-wheel may be cut so as to be adapted for making any number of courses or colors desired. In fig. 3 is shown a flat circular disk, P, the outer periphery of which is provided with a number of teeth, u, corresponding to the number of courses, and serves a similar office to that of the ratchet-wheel G, while its upper surface is provided with four flanges, v w x y, which extend partially around the circumference of a circle of the diameter required, the portions of the circumference between 9 and 10, and 11 and 12, being smooth, and flush with the upper surface of the disk. These flanges v w x y are provided with notches, z, the flanges so constructed serving to take the place of the cam-wheel H. This disk P fits over a stud, Q, corresponding to that marked I in fig. 1, and is revolved by a single driver or a pair of drivers, alternately engaging within its ratchet-teeth, u. R R R R are four levers, corresponding to the number of flanges v w x y, and, consequently, to that of the colors to be woven. These levers R are of unequal length, and are pivoted at one end to the stud Q, while their other ends are provided with projections, 13, which fall at stated times into a notch in an arm rising from or forming a part of the guide-bar to be moved.

The under sides of these levers are also provided with other projections, 14, which, as the circular disk P is revolved under them, bear on the flanges v w x y, and drop at the required times into the notches z, thus causing the projections 14, through the forked pieces attached thereto, to engage with the guide-bars, only one of which is operated at once. The distance between the notches z is such as to insure the projection at the end of its lever being engaged just long enough to make a single course or any odd number of courses, of the color required, after which another lever is made to engage with another bar, to produce any number of odd or even courses of any other color, both drivers F being employed. When the cam-wheel H, with its ratchet, G, is used in connection with a single driver, F, any number of even courses of three or four colors may be woven, even courses of two colors only having been previously made by the use of a single driver. It is evident, that by increasing the number of flanges of the flat circular wheel or disk P, and the number of levers R, a greater number of guide-bars may be operated, so as to weave five, six, or more colors, and other goods besides hose may be woven, without departing from the spirit of my invention.

When a new color is to be woven, no one of the levers engages with a guide-bar while the slide is going back in its grooved way a, for the purpose of taking the new color, which operation is technically termed a "drawback."

Claims.

What I claim as my invention, and desire to secure by Letters Patent, is—

A ratchet-wheel, G, with a single cam or eccentric, H, operated by a single driver, F, for weaving any even number of courses of three or four colors, substantially as set forth.

I also claim a ratchet-wheel or disk, P, provided with three or more flanges, constructed as described, in combination with a corresponding number of levers, R R, and operated by two drivers, F, for weaving odd or even courses of three or more colors, substantially as and for the purpose specified.
